UNITED STATES PATENT OFFICE

121,274

DESIGN FOR A WRAPPING PAPER OR SIMILAR ARTICLE

Annette Fontaine and Sylvia Haggander, New York, N. Y., assignors to Cresca Company, Incorporated, New York, N. Y., a corporation of New York

Application May 18, 1940, Serial No. 92,463

Term of patent 14 years

To all whom it may concern:

Be it known that we, Annette Fontaine and Sylvia Haggander, citizens of the United States of America, and residing in New York city, New York, have invented a new, original, and ornamental Design for a Wrapping Paper or Similar Article, of which the following is a specification, reference being had to the accompanying drawing, forming part thereof.

The figure is a plan view of a wrapping paper or similar article showing our new design.

We claim:

The ornamental design for a wrapping paper or similar article, as shown.

ANNETTE FONTAINE.
SYLVIA HAGGANDER.
